(57) CLAIM

The ornamental design for an electronic cigarette, as shown and described.

DESCRIPTION

FIG. 1 is a left side perspective view of an electronic cigarette, showing my new design.

FIG. 2 is a right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top view thereof.

FIG. 8 is a bottom view thereof; and,

FIG. 9 is a perspective view thereof shown in an environment of use with a capsule inserted into the electronic cigarette.

The broken lines in the drawings that depict portions of the electronic cigarette form no part of the claimed design. The additional broken lines, depicting a capsule shown in FIG. 9 depict environmental subject matter only and form no part thereof.
